F. J. LAPONTE

BROACHING TOOL

Original Filed Dec. 2, 1921

Fig. 3.

Inventor:
Francis J. Lapointe,
by Walter E. Lombard,
Atty.

UNITED STATES PATENT OFFICE.

FRANCIS J. LAPOINTE, OF ANN ARBOR, MICHIGAN.

BROACHING TOOL.

Original application filed December 2, 1921, Serial No. 519,500. Divided and this application filed April 16, 1923. Serial No. 632,318.

To all whom it may concern:

Be it known that I, FRANCIS J. LAPOINTE, a citizen of the United States of America, and a resident of Ann Arbor, in the county of Washtenaw and State of Michigan, have invented certain new and useful Improvements in Broaching Tools, of which the following is a specification.

This invention relates to broaching tools 10 and particularly to tools of this character designed to cut and finish round holes.

The present invention consists in forming the tops of the teeth of an equal thickness with the backs thereof connected to the bevel 15 portions of the broach by a slight shoulder, the face of which is parallel with the front face of the teeth.

The invention further consists in certain 20 novel features of construction and arrangement of parts which will be understood readily by reference to the description of the drawings and to the claims to be hereinafter given.

For the purpose of illustrating the invention, one preferred form thereof is shown 25 in the drawings, this form having been found to give satisfactory and reliable results, although it is to be understood that the various instrumentalities of which the 30 invention consists can be variously arranged and organized, and that the invention is not limited to the precise arrangement and organization of the instrumentalities as herein shown and described, except as required 35 by the scope of the appended claims.

Of the drawings:

Fig. 1 represents an elevation of a broach embodying the principles of the present invention.

Fig. 2 represents a section of same on line 2, 2 on Fig. 1, and

Fig. 3 represents a greatly enlarged sectional detail showing the differences in formation of the successive teeth.

Similar characters indicate like parts throughout the several figures of the drawings.

In the drawings, 10 is a member having a cylindrical portion 11 at one end and another cylindrical portion 12 at the opposite end.

The portion 12 is of larger diameter than the portion 11 and is adapted to burnish the hole when the broaching has been completed.

Adjacent to the cylindrical portion 12, the

member 10 is provided with a plurality of annular cutting members 13 having the same diameter as the portion 12.

These cutting members 13 are preferably spaced an equal distance apart. 60

Between these cutting members 13 and the portion 11 are a plurality of cutting members 14 which are spaced from each other a distance considerably greater than the distance between the cutting members 13. 65

Preferably the space between every alternate pair of cutting members 14 is greater than the space between the other pairs as clearly indicated in the drawings.

Usually in broaches of this character, the 70 cutting members 13 and 14 are backed off slightly from the cutting edge, and the member 10 is then provided with a groove 15 to receive the chips cut by the tool.

One wall of this groove 15 forms the 75 front face 16 of the cutting members 13, 14 while the other wall 17 is inclined to the rear edge of the cutting tooth.

Each cutting member 14 has a diameter 80 slightly greater than the cutting member in advance thereof.

When the broaches are straightened in the manufacture thereof, it is extremely difficult to straighten them so that they will run true within .005 to .010 of an inch and 85 it is often necessary to grind them running this much out of true.

The consequence is that it is difficult to secure a perfectly round periphery as some 90 parts of the periphery will be wider than other parts and this prevents the grinding wheel from cutting as freely when on a wider portion as it does on a narrow portion of said periphery.

This is particularly true in the manufacture of small broaches. 95

This is also true when the teeth are backed off in an attempt to secure a uniform land for a cutting edge.

Unless the land is of uniform width, an 100 imperfect result will be obtained during the broaching operation due to the fact that if one side of the land is wider than another side, it will cut freer on that side and will crowd the broach over to one side with the 105 result that a hole is produced that is not in proper relation to the original hole in the work being operated upon.

By providing the shoulder or rear face 18, these difficulties are entirely obviated 110

and a perfectly round tooth may be ground and when the broach is in use, owing to the uniform width of the periphery of the tooth, a perfectly round hole will be cut in proper relation to the original hole in the work. Moreover, the construction of the broach is greatly simplified by making the teeth with the shoulder or face 18.

The teeth 14 are preferably provided with 10 a plurality of peripheral nicks or indentations 19, the nicks in each tooth being out of alinement with the nicks in the teeth adjacent thereto.

In applicant's broaching tool, it is quite 15 essential that the two faces 16, 18 be parallel, for in the construction of the broach, the device must be tempered before the cutting members 14 are ground; and in tempering, the broach is liable to become distorted and while distorted the cutting members 20 must be ground so that these members will be in axial alinement when the grinding is completed.

If the larger end of the cone-shaped portions 25 17 registered with the periphery of the cutting members 14, it is obvious that with the entire tool distorted to some extent, when the grinding of the cutting member 14 is effected, the width or thickness of the 30 periphery of the cutting member would be liable to vary at different points about the periphery.

In such a case, the tool would operate 35 imperfectly and would not cut a clean, round hole, but would, on the contrary, be liable to move sidewise to some extent and the hole cut would, as a consequence, be out of round.

This would be very objectionable and to 40 obviate this difficulty, applicant has provided the cone-shaped connecting portion 17, the diameter of the end abutting the rear face of the cutting member 14 being slightly less than the diameter of said rear 45 face 18.

The cone-shaped portions 17 stiffen the tool and reduce to a minimum the distortion during the tempering.

By causing the larger end of the conical 50 portion 17 to join the cutting member 14 at a point slightly inside the periphery of the cutting member 14, a rear face 18 is formed absolutely parallel to the front face 16 which extends inwardly from the periphery of the cutting member approximately 55 six times as far as the rear face 18 extends inwardly from said periphery.

When thus constructed, even if the tool is somewhat distorted during tempering, the thickness of the cutting member 14 will be 60 the same throughout, after the grinding operation has been completed.

By providing this rear face 18, this desired result can always be obtained, even if the portions 17 are slightly out of alinement, and a tool formed in which the cutting members will be in alinement and capable of cutting a round hole without any tendency for the tool during the cutting operation to veer sidewise. 70

The present invention is a division of the application filed December 2, 1921, Ser. No. 519,500.

It is believed that the operation and many advantages of the invention will be understood readily without further description. 75

Having thus described my invention, I claim:

1. A device of the class described, provided with a plurality of cutting members, 80 the front and rear faces of which are parallel and perpendicular to the axis of said cutting members, each pair of said cutting members being connected by a cone-shaped portion, the larger end of which adjacent 85 the rear face of a cutting member has a diameter slightly less than that of said rear face.

2. A device of the class described, provided with a plurality of cutting members, 90 the front and rear faces of which are parallel and perpendicular to the axis of said cutting member, each pair of cutting members being connected by portions, the diameter of the end connected to the rear face of 95 a cutting member being slightly less than that of said rear face and greater than the diameter of the end connected to the front face of the next cutting member.

3. A device of the class described, provided with a plurality of cutting members, 100 the front and rear faces of which are parallel and perpendicular to the axis of said cutting members, the front face of each cutting member extending inwardly from the 105 periphery of said cutting member approximately six times as far as the rear face extends inwardly from said periphery.

Signed by me at Ann Arbor, Mich., this 12th day of April, 1923.

FRANCIS J. LAPOINTE.
